UNITED STATES PATENT OFFICE.

GEORGE A. GLASS, OF NEWARK, NEW JERSEY.

METAL SIGN.

1,203,532.

Specification of Letters Patent. Patented Oct. 31, 1916.

Application filed October 14, 1915. Serial No. 55,873.

To all whom it may concern:

Be it known that I, GEORGE A. GLASS, a citizen of the United States, and a resident of Newark, in the county of Essex and State of New Jersey, have invented a new and useful Improvement in Metal Signs, of which the following is a specification.

My present invention relates generally to signs and more particularly to metal signs wherein a polished plate is used to form the field work or background of the letters, the primary object of my invention being to permit of thorough cleaning and polishing of the background or field work of the sign without danger of smearing, defacing, or otherwise marking the letters themselves. In accomplishing this object I utilize a skeleton front plate having the outlines of the letters cut out therefrom and a letter plate upon the face of which the front outline plate is detachably mounted, the letter plate having either a flat surface to form surface letters which are etched out of a polished plate in the usual manufacture of such signs, or provided with raised letters adapted to project through the outlines of the front plate to form what is generally known as an embossed sign, the letter plate being in either instance of a suitable color to form the letters through the outlines of the front plate and the sign in either instance including a back plate detachably mounted against the rear surface of the letter plate and provided with projections to extend through apertures in the letter plate where necessary to form the inner field work or background of certain letters having inner openings entirely surrounded by portions of the letters.

The particular manner in which the invention is practised will be clearly understood from the following description, referring to the accompanying drawings forming a part of this specification, and in which—

Figure 1 is a front view of a sign complete within a frame and embodying my invention. Fig. 2 is a horizontal section therethrough taken substantially on the line 2—2 of Fig. 1. Fig. 3 is a rear elevation of the front outline or skeleton plate, the intermediate letter plate and the black plate secured in proper relation. Fig. 4 is a section through the sign taken substantially on the line 4—4 of Fig. 1. Fig. 5 is a vertical section through a sign having its letters formed of a style known as surface lettering. Fig.

6 is a front elevation of a portion of the sign shown in Fig. 5, and Fig. 7 is a front face view of the back plate having projections forming the inner field work or background 60 for certain letters.

Referring now to these figures, and more particularly to Figs. 2, 4 and 5, it will be seen that the letter plates indicated at A in Figs. 2 and 4, and A' in Fig. 5 are interposed between the front outline or skeleton plates B and the back plate C, the letter plates and back plates having side openings D through which extend studs D' projecting rearwardly from the rear surfaces or front 70 outline of skeleton plate B, the back plate having swinging hooks D² engageable through transverse apertures in these studs, in order to lock the several plates detachably 75 in the relation before mentioned.

In Figs. 1, 2 and 4 the letter plate A has raised letters indicated at A² projecting through the outlines B' of the front plate B and is provided with openings corresponding to the inner field work or background 80 B² of certain letters having inner openings entirely surrounded by portions of the letters, such as B, R and O, as in Fig. 1, these openings receiving the projecting studs C' placed upon the face of the back plate C as 85 shown in Fig. 7, at points coincident with the openings, so as to project within the letters themselves to parts flush with the front surface of the front outline or skeleton background plate B as will be particularly 90 seen from Figs. 2, 4 and 5.

In Figs. 5 and 6 the lettering is of the type known as surface lettering, which in the usual metal sign involves etching the letters from the front face of a polished plate 95 and enameling the same, the intermediate letter plate A' being, in accordance with my invention in this instance, flat throughout so that portions of a surface show through the outlines B' of the front plate B as seen in 100 Fig. 6, the letter plate in this instance, as in the instance before described, being provided with apertures coincident with the inner field work or background B² of the letters to receive the projections C' of the 105 back plate C in the same manner these are received in the apertures of the letter plate A before described.

The result of a construction of this character is to enable the ready disassociation of 110 the field work or background of the letters from the differently colored letters them-

5 selves in order that the former may be readily polished or otherwise resurfaced and renewed without smearing, scratching, or otherwise marring or defacing the letters themselves. Where letters such as B, R, and O are utilized in a sign it is just as important to detach the inner field work of these letters and hence the back plate C carrying the projections forming such inner field 10 work are readily detachable in substantially the same manner as the front outline or skeleton plate B.

15 The sign thus described may be utilized in various ways and mounted in any desirable manner. In Figs. 1, 2 and 3, in particular, I have shown one manner in which the sign thus constructed may be associated within a frame E in a manner permitting its ready detachment, and the ready detachment of 20 its several parts, the front outline or skeleton plate B being to this end provided with horizontally projecting studs B³ at one side adapted to enter sockets E' in one side of the frame for the reception of such studs as 25 shown in Fig. 2, and having upon its rear face and at its opposite side a lock B⁴ for engagement with the opposite side frame as indicated in dotted lines in Fig. 1 and in full lines in Fig. 2. To this end also the 30 front outline or skeleton plate B has a key opening B⁵ and may be provided with a pivot swinging cover plate B⁶ to normally cover such key opening. Thus the letter plate and its field work plates detachably 35 mounted in the proper relation as before described, and particularly shown in Fig. 3, may be detachably mounted within the frame in such manner as to prevent their unwarranted removal and permit of their ready 40 disassociation by those properly having access to the several parts for cleaning and renewing the same.

45 It is to be appreciated, of course, in the practical use of the invention that a sign may be made up partly of surface letters and partly of raised letters as is now common practice in connection with the ordinary signs, in view of the fact that in my invention the parts are associated the same for 50 one style as for the other. It is further to

be understood as a matter of course that the surfacing and coloring of the letters and background may be varied within limits just as wide as those common to the art at present.

I claim:—

55 1. A sign comprising a letter plate having apertures, a front outline or skeleton plate forming the outer field work for the letters and through which portions of the letter plate show and a back plate having projections extending through the apertures in the letter plate to form the inner field work of certain letters having inner openings entirely surrounded by portions of the letters, and means for holding the plates in detachable relation to permit of their ready disassociation, for the purposes described. 60

65 2. A sign comprising a front outline plate, a letter plate having apertures therethrough coincident with the openings of certain letters having inner openings entirely surrounded by portions of the letters, and a back plate detachable from the letter plate and having projections coincident with and adapted to extend through the apertures of 70 the letter plate to form the inner field work 75 of the letters before mentioned.

80 3. A sign substantially as described, comprising a back plate having portions which form the inner field work of certain letters having inner openings entirely surrounded by portions of the letters, a letter plate having letters whose openings correspond with the said portions of the back plate, and a front outline or skeleton plate having openings outlining the letters, a frame, and a locking device for securing the front outline or skeleton plate in the frame, substantially 85 as set forth.

90 4. A sign substantially as described comprising a front outline plate, a letter plate at the rear of the outline plate, a back plate at the rear of the letter plate, said outline plate having apertures through which portions of the letter plate show, and said letter plate having apertures through which in 95 turn portions of the back plate show, and means for securely holding the several plates together.

GEORGE A. GLASS.
